ROCK DRILL

John Clark Curtis, Claremont, N. H., assignor to
 Sullivan Machinery Company, a corporation of
 Massachusetts

Application July 8, 1937, Serial No. 152,609

33 Claims. (Cl. 121—19)

This invention relates to rock drills, and more particularly, but not exclusively, to a rock drill of the pressure fluid actuated, hammer type having improved fluid distribution means for the hammer motor.

An object of this invention is to provide a rock drill of an improved design wherein the efficiency is greatly improved and the component parts are made relatively rugged and durable in construction. Another object is to provide, in a rock drill of the hammer type, improved fluid distribution means for the drill hammer motor whereby pressure fluid is distributed to the motor cylinder in a novel and improved manner. A further object is to provide an improved fluid distribution means having improved fluid distributing valve mechanism and flow passage arrangements whereby the motive fluid is distributed to the motor cylinder in an improved manner. Another object is to provide an improved valve mechanism of the multi-valve type embodying a pair of cooperating, relatively movable, valve elements for controlling the flow of pressure fluid to the motor cylinder in an improved manner. A further object is to provide, in a valve mechanism of the above character, an improved flow passage arrangement associated with the valve elements together with a novel throwing means for the valve elements whereby the speed of operation and efficiency of the drill hammer motor are greatly improved. Still another object is to provide, in a valve mechanism of the above character, an improved valve construction and associated flow passage arrangement whereby the hammer piston of the hammer motor is actuated to deliver an extremely powerful blow to the drill steel, the valve elements of the improved valve structure being arranged in a novel manner so that fluid is distributed to the motor cylinder to cause the hammer piston to strike an unimpeded, uncushioned blow on the drill shank, while, at the same time, the consumption of pressure fluid is reduced to a minimum. These and other objects and advantages of the invention will, however, herein-after more fully appear.

In the accompanying drawings there is shown for purposes of illustration one form which the invention, in its various aspects, may assume in practice.

In these drawings—

Fig. 1 is a view in longitudinal vertical section through a rock drill incorporating an illustrative embodiment of the invention.

Fig. 2 is an enlarged cross sectional view taken

substantially on line 2—2 of Fig. 1, the drill hammer motor being partially shown in end elevation.

Fig. 3 is an enlarged cross sectional view taken substantially on line 3—3 of Fig. 1.

Fig. 4 is an enlarged cross sectional view taken substantially on line 4—4 of Fig. 1.

Fig. 5 is a rear end elevational view of the front valve element.

Fig. 6 is a front end elevational view of the rear valve element.

Fig. 7 is an enlarged fragmentary sectional view taken in the plane of Fig. 1, showing details of the improved fluid distribution means.

Figs. 8 and 9 are views similar to Fig. 7 showing the valve elements and hammer piston in different positions.

Fig. 10 is a cross sectional view taken substantially on line 10—10 of Fig. 7.

Fig. 11 is a cross sectional view taken substantially on line 11—11 of Fig. 7.

Fig. 12 is a developed view in longitudinal section taken substantially on line 12—12 of Fig. 10, showing certain of the fluid distributing passages and the valve throwing passage.

Fig. 13 is a cross sectional view taken substantially on line 13—13 of Fig. 7.

Fig. 14 is a detail sectional view taken on line 14—14 of Fig. 2.

Fig. 15 is a detail sectional view taken on line 15—15 of Fig. 2.

Fig. 16 is an enlarged fragmentary sectional view taken in the plane of Fig. 8, showing the distributing valves both in seated position.

In the illustrative embodiment of the invention, there is shown a pressure-fluid-actuated, hammer rock drill of the mounted drifter type, although it will be evident that various features of the invention may be embodied in rock drills of various other types.

In this construction, the reference character 1 generally designates the drill hammer motor, 2 the guide shell, 3 the feeding means for the hammer motor, 4 the chuck mechanism and 5 the improved throttle valve mechanism. The motor cylinder 6 has lateral guides 7, 7 slidably received in longitudinal guideways 8, 8 formed on the guide shell 2, and the latter has a bottom trunnion support 9 adapted to be clamped in the usual saddle mounting of a tripod or column. 45 The feeding means 3 comprises a feed screw 10 journaled at its opposite ends within bearing yokes 11, 11 secured to the opposite ends of the guide shell and having at its rear end a manual rotating handle 12. The feed screw threadedly 50

55

engages a non-rotatable feed nut 13 fixed within the bore of a depending boss 14 formed integral with the motor cylinder 6. As the feed screw is rotated by the handle 12 relative to the non-rotatable feed nut, the drill hammer motor is fed either forwardly or rearwardly along the shell guideways, depending upon the direction of feed screw rotation. As the guide shell 2 and feeding means 3 are of a conventional design, further detailed description thereof is unnecessary.

Now referring to the improved hammer motor 1, it will be noted that the motor cylinder has a piston chamber or bore 15 containing a reciprocating hammer piston 16 having a piston head 17 fitting the cylinder bore and a forwardly projecting striking bar 18 adapted to deliver impact blows to the shank of a usual drill steel 19. The piston striking bar is guided in a bore 20 formed in a front buffer ring 21 having an external flange 22 at its rearward end fitting the forward end of the cylinder bore to provide a front cylinder head. This buffer ring has a portion 23 fitting in a bore 24 in the front cylinder extension 25, and has an external flange 26 abutting the front end of the cylinder extension, in the manner clearly shown in Fig. 1. The buffer ring extension has a bore 27 providing an elongated bearing for a chuck sleeve 28 rotatably mounted at its forward end within a chuck housing 29. This chuck housing abuts the forward face of the flange 26 and has a bore receiving the forward portion of the buffer ring extension 23. Within a bore 30 formed in the chuck sleeve is a chuck bushing 31 abutting an inwardly directed shoulder 31^a on the chuck sleeve and having a bore for receiving the shank of the drill steel. The chuck bushing is held in position within the chuck sleeve by means of a combined driver and locking member 32 threaded at 33 within the forward portion of the chuck sleeve. The chuck housing has an inwardly directed flange 34 providing a shoulder against which the forward end of the chuck sleeve abuts, and this flange provides an axial opening through which the forward portion of the member 32 extends. Upon unscrewing of the member 32 from the chuck sleeve, this member may be withdrawn forwardly from the chuck housing to obtain access to the chuck bushing for replacement purposes. Forward release of the member 32 from the chuck housing is also desirable in the event of the lugs and the rear end of the drill shank becoming headed over or distorted due to the repeated impacts thereon, preventing withdrawal of the steel shank from the chuck bushing and the locking member. The chuck sleeve is formed with an external flange 35 arranged between the forward end of the buffer ring extension 23 and a shoulder 36 formed within the chuck housing. The chuck housing and the buffer ring extension provide elongated bearings for the chuck sleeve so that the latter is maintained in proper alignment with the cylinder. The driver and locking member 32, as shown in Fig. 4, has internal driving lugs 37 engageable with lugs 38 on the drill steel shank, and is formed with a key opening 39 for receiving the steel shank lugs. When the lugs on the steel shank are inserted through the key opening within the driver member and the steel is turned to bring the shank lugs 38 into driving engagement with the lugs 37, the shank lugs are brought out of registry with the key opening so that the steel shank is locked against forward displacement from within the driver member. Pressed in a bore 40 formed within the rearward portion

of the chuck sleeve is a chuck nut 41 held against rotation relative to the chuck sleeve by means of a key pin 42 fitted in registering grooves on the chuck sleeve and chuck nut. When the chuck sleeve is removed from within the buffer ring 5 extension bore, the chuck nut may be withdrawn axially through the rear end of the chuck sleeve for replacement purposes.

As is usual in rock drills of the type disclosed, means is provided for rotating the drill steel as it 10 is percussively actuated by the hammer piston, comprising a rotatable pawl carrier 43 carrying usual spring-pressed pawls engageable with the teeth of a non-rotatable ratchet ring 44. Formed integral with the pawl carrier is a rifle bar 45 15 having spiral grooves slidably interlocked with spiral keys formed on a rifle nut 46 fixed within the hammer piston. As the hammer piston moves forwardly to effect its working stroke, i. e., to deliver an impact blow to the shank of the drill 20 steel, the pawls of the pawl carrier slip over the ratchet teeth so that the hammer piston delivers an unimpeded blow to the steel shank. During the return stroke of the hammer piston, the pawls on the pawl carrier engage the ratchet 25 teeth to hold the rifle bar against rotation, and, as a result, the hammer piston is rotated. The rotary motion of the hammer piston is transmitted to the drill steel shank through straight grooves 47 on the piston striking bar slidingly 30 interlocked with straight keys on the chuck nut 41, rotating the latter with the piston, and, as a result, effecting rotation of the chuck sleeve, chuck bushing and driver member, and hence the drill steel is locked within the driver member. It will thus be seen that as the drill steel is percussively actuated by the hammer piston, it is intermittently rotated, in the manner well understood by those skilled in the art.

The improved fluid distribution means will now 40 be described. Formed in a rearward extension of the motor cylinder is a bore 50 arranged in axial alignment with the motor cylinder bore, and arranged in this extension bore is a valve seat plate 51 constituting the rear cylinder head and having 45 a sleeve-like portion 52 projecting axially from its rear face, the latter providing a bearing for the rifle bar 45. Also arranged in the extension bore 50 and abutting the rear face of the plate 51 is a valve box 53 having a bore 54 of a uniform 50 diameter throughout its length. The plate 51 forms a front closure for the bore of the valve box 53 while the rear end of the bore is closed by a valve box cover 55 likewise arranged in the extension bore and abutting the rear face of the valve box 53. Arranged within the rearward portion 55 of the extension bore 50, behind the ring 44, is a ratchet collar 56. The collar, ratchet ring and cover are maintained against rotative movement within the bore 50 by a dowel pin or key 57 fitted in registering grooves in the cooperating parts and in the cylinder member 6. Engaging the ratchet collar is a back head 58 adapted to be clamped to the rear end of the cylinder to hold the parts above described within the extension bore, and the front chuck housing is also clamped to the front end of the cylinder to hold the buffer ring and chuck sleeve in position. The back head and the front chuck housing are secured to the cylinder in any appropriate manner, as by usual side rods 59, 59 (Figs. 3, 10, 11 and 13).

Referring more particularly to the specific valve structure, it will be observed that reciprocably mounted in the bore 54 of the valve box is a pair of cooperating, relatively movable, fluid 75

distributing valve elements 60 and 61, herein preferably of the sleeve type arranged in telescopic relation and respectively controlling the flow of pressure fluid to the opposite ends of the 5 cylinder bore, in the manner to be later more fully explained. The rear valve element controls admission and cut-off for the front end of the cylinder, the front valve element like functions for the rear end of the motor cylinder. The rear 10 valve element 60 comprises a rearwardly located external flange 62 fitting the valve box bore, and a forwardly projecting sleeve-like body portion 63, telescoping over the rearwardly-extending sleeve-like body portion 64 of the front valve element 61. Formed on the rear valve element is an inwardly directed internal flange 65 cooperating with a forwardly projecting annular portion 66 integral with the valve box cover 55, to meter motive fluid for the front end of the cylinder. 15 The front valve element has a similar inwardly directed internal flange 67 cooperating with the sleeve-like projection 52 integral with the valve seat plate 51 to meter the motive fluid for the rear end of the motor cylinder. This metering 20 function will be later more fully described. Fitting the valve box bore and formed at the front end of the front valve 61 is an external flange 68. The opposite end faces of the valves 60 and 61 are formed with annular seating portions 69 25 and 70 respectively, the former adapted to seat against the front face of the valve box cover 55 and the latter to seat against the rear face of the plate 51. The front face of the cover 55 is formed with an annular recess 71 communicating 30 with the valve receiving bore at the rear side of the valve flange 62 and this recess is connected through a pair of ports 72, 72 in the cover 55 with ports 73, 73, and these latter in turn communicate with passages 74, 74 formed in the cylinder 35 (Fig. 12) and communicating through ports 75 with the forward end of the cylinder bore. The rear face of the plate 51 is formed with an annular recess 76 communicating with the valve receiving bore at the forward side of the valve 61, and this recess is connected by a series of passages 77 with the rear end of the cylinder bore. Formed externally on the valve box 53 is an annular groove 78 communicating through a port 79 with the space between the valves 60 and 61, and 40 this groove is connected, as shown in Fig. 12, by a port 80 with a throwing passage 81, the latter in turn communicating through ports 82 and 83 with the cylinder bore at points spaced longitudinally of the latter.

55 The means for supplying pressure fluid to the valve box bore comprises a throttle valve 84 forming a part of the throttle valve mechanism 5. This throttle valve is arranged within a transverse bore 85 formed in the back head 58. 60 The throttle valve is provided with an internal pressure chamber 86 connectible through a port 87 with a port 88 formed in the back head and communicating with a pressure chamber 89 formed between the ratchet collar 56 and the 65 back head. This pressure chamber 89 is connected through a series of ports 90 with an annular recess 91 formed in the forward face of the ratchet collar 56, and this recess communicates through the spaces between the ratchet teeth and 70 pawl carrier with an annular recess 92 formed in the rear face of the valve box cover 55. The recess 92 is connected through a series of ports 93 with a large axial passage 94 extending through the annular projection 66 on the valve box cover 75 and communicating with the internal space

within the valve elements 60 and 61. As above indicated, pressure fluid may flow from within the space between the valve elements, past restricted clearance spaces 95 and 96 at the inner edges of the internal valve flanges 65 and 67 respectively, to provide metering of the fluid flowing past these internal valve flanges so that the flow of pressure fluid to the supply passages is always maintained constant irrespective of any wear of the valves, the valves being guided solely 10 at the exterior peripheries of the external flanges thereof which slidably fit the valve box bore 54. Formed within the wall of the cylinder bore substantially midway between the ends of the cylinder is an annular exhaust groove 97 connected 15 directly to atmosphere through a lateral exhaust port 98 (see Fig. 11). This exhaust groove lies between the points of communication of the ports 82 and 83 with the cylinder bore. The valve chamber at the front side of the front valve element 61 is connected to the rear end of the cylinder bore through a restricted leak passage 99, 20 while the recess 71 is connected to the recess 92 by a restricted leak passage 100.

Now referring again to the improved throttle 25 valve structure, it will be noted that the throttle valve is of cylindric form, as shown in Fig. 2, and is provided with a valve stem 102 projecting outwardly through a bore 103 formed in the back head. Fitted on this valve stem is a handle hub 104 having a lateral boss 105 in which is suitably threaded at 106 a valve operating handle 107. This valve handle has a tapered inner end 108 adapted to seat within a tapered socket 109 formed within the valve stem. ally through the drill steel to the bottom of the drill hole.

- The mode of operation of the improved fluid distribution means will be clearly apparent from 5 the description given. When the parts are in the position shown in Fig. 7, pressure fluid may flow from the interior of the throttle valve 24 through ports 87, 88, chamber 89, ports 90, recess 91, through the spaces between the teeth of the 10 ratchet ring, groove 92, ports 93 and the axial passage 94 to the internal chamber within the valve elements. Pressure fluid flows through the restricted clearance space 95 between the inner 15 peripheral edge of the internal flange 65 on the rear valve element and the exterior peripheral surface of the annular projection 66, through the valve box bore past the rear face of the rear valve element and through the annular recess 71, ports 72, 73, passages 74 and ports 75 to the forward 20 end of the cylinder bore at the front side of the piston head, the pressure fluid acting on the front pressure area of the hammer piston to drive the latter rearwardly to effect its return stroke. The rear end of the cylinder bore is, at this time, 25 connected to exhaust through the exhaust groove 97 and exhaust passage 98. As the hammer piston moves rearwardly, the leading (rearward) edge of the piston head overruns the exhaust groove 97, cutting off communication of the rear 30 end of the cylinder bore with the exhaust, and upon continued rearward movement of the hammer piston, the rearward end of the piston head covers the port 82 and the forward end of the piston head uncovers the port 83, and pressure 35 fluid then flows from the front end of the cylinder bore through the port 83, throwing passage 81 and port 80, through the annular groove 78 and port 79, into the annular space between the valve flanges 62 and 68, and the pressure in said 40 annular space immediately throws the rear valve element 60 rearwardly from its position shown in Fig. 7 to its position shown in Fig. 8, causing the annular seating portion 69 on the valve element 60 to seat against the front face of the valve box 45 cover 55 and shut off flow of pressure fluid to the forward end of the cylinder bore. This pressure in the space between the valve flanges also acts to hold the forward valve in closed position. Accordingly, the piston continues to 50 move rearwardly, and as it moves towards the rear cylinder head the pressure fluid trapped within the rear end of the cylinder bore is compressed, and when the front edge of the piston head uncovers the exhaust groove 97 the pressure 55 within the space between the flanges 62 and 68 will be vented to exhaust through passage 79, groove 78, port 80, passage 81, port 83, and the cylinder bore, while the valve bore at the rear side of the rear valve element 60 is connected to exhaust through the passages 74, and, 60 as a result, the compression pressure built up by the piston within the rear end of the cylinder bore acting on the front pressure area of the front valve element 61 is effective to throw this valve element rearwardly from the position 65 shown in Fig. 8 to the position shown in Fig. 9. When the parts are in the position shown in Fig. 9, pressure fluid may flow from the internal chamber within the valve elements 60, 61, 70 through the restricted clearance space 96 between the inner peripheral edge of the internal valve flange 61 and the exterior periphery of the sleeve 52, through the valve bore at the forward side of the front valve element 61 and through 75 the annular recess 76 and ports 77 to the rear

end of the cylinder bore at the rear side of the hammer piston. At this time the front end of the cylinder bore is connected to exhaust through the exhaust groove 97 and exhaust passage 98, as previously explained.

The pressure fluid acting on the rear pressure area of the hammer piston now moves the latter forwardly to effect its working stroke, i. e., to deliver an impact blow to the shank of the drill steel. As the hammer piston moves forwardly, 10 the forward edge of the piston head first covers the exhaust groove 97, cutting off communication of the forward end of the cylinder bore with exhaust, and upon continued forward movement of the hammer piston, the forward end of the 15 piston head covers the port 83 and the rearward edge of the piston head thereafter uncovers the port 82 of the throwing passage 81, thereby admitting pressure fluid from the space at the rear 20 of the piston through the groove 78 and port 79 to the space between the flanges 62 and 68 of the valves. Due to the restriction at 96 between the internal pressure chamber within the valve elements and the valve receiving bore at the forward side of the internal valve flange 61, and the 25 relatively rapid flow of pressure fluid from the front end of the valve bore to the rear end of the cylinder bore through the ports 77, the pressure of the fluid at the rear of the internal valve flange 61 is substantially greater than that in 30 the valve bore at the front side of the flange. As a result, when the hammer piston reaches the position shown in Fig. 8, and pressure at cylinder pressure admitted through port 82, passage 35 81, etc. enters the space between the valve flanges, the pressure of the fluid within the space between the external valve flanges and the pressure of the fluid at the rear side of the valve flange 61 overcomes the pressure of the fluid at the forward side of the front valve element 40 61, thereby throwing the front valve element from the position shown in Fig. 9 forwardly to the position shown in Fig. 8. At this time, the annular seating portions 69 and 70 on the remote 45 faces of the valves are both momentarily held seated against the end surfaces of the valve bore and the supply of pressure fluid to the opposite ends of the cylinder bore is completely cut off (see Figs. 8 and 16). Forward movement of the hammer piston continues under the expansive 50 action of the pressure fluid within the rear end of the cylinder bore. When the forward end of the forwardly moving hammer piston overruns the exhaust groove 97, a compression pressure starts to build up at the forward side of the piston 55 since the fluid within the forward end of the cylinder can not escape. The compression pressure continues to build up with the forward movement of the hammer piston, but not to a value sufficient to move the valve element 60 60 from its seat against the pressure between the external valve flanges, until after the port 82 is connected to exhaust as a result of the piston's uncovering the exhaust groove 97. When 65 the rear end of the piston head commences to uncover the exhaust groove 97, however, release for the rear end of the cylinder will occur and concurrently, the pressure which has been acting in the annular space between the external flanges on the valves will be vented to the exhaust through the passage 81 and port 82; and the compression pressure transmitted from the front end of the cylinder to the rearward surface of the external flange 62 on the rear of the valve 60, through the port 75, passage 74, and 70 75

ports 73 and 72, will cause the rear valve 60 to move to the position of Fig. 7 and admit fluid for the rearward traverse of the motor piston. It will be evident, however, that the motor piston will substantially complete its full working stroke before any motive fluid is admitted to the forward side thereof, and accordingly a largely unimpeded blow will be struck the shank of the drill steel—a much less impeded blow than would be possible with any construction utilizing a single valve, such constructions permitting but little time between cut-off at the rear end of the cylinder and admission to the forward end of the cylinder.

15 The further operation of the motor will consist of repetitions of the cycles which have been described.

It will be noted that throwing of the valve which controls the supply of pressure fluid to a given cylinder end is effected in an opening direction by compression pressure, upon the venting of the pressure from the annular space between the external flanges upon the two valves, and that the opposite movement of such valve is effected by pressure admitted between such valve flanges from the cylinder bore, such opposite movement facilitated by the fact that the relatively free flow to the cylinder from the spaces beyond the restricted annular passages bounded exteriorly by the internal valve flanges results in less strong pressures holding the valves in open position than would exist were the restriction of flow, so to speak, not provided by these flanges.

35 The functions of the passages 99 and 100 will be readily understood. The passage 99 will admit pressure from the space inside the valves, should both of these valves be closed and the piston be at the rear end of the cylinder, into the restricted space to the rear of the piston, and this pressure will pass back through the port 77 and groove 76 and act on the forward side of the flange 68, and accordingly, the forward valve will be moved to open position and the motor will then begin to operate in a normal manner.

45 In the case of the passage 100, if the piston happens to be at the forward end of the cylinder and both valves closed when air is turned on, the pressure will pass through the passage 100 and act upon the rearward surface of the flange 62 and move the rearward valve 60 into open position and cause the motor to start. In the normal operation of the motor, the passages 99 and 100 play no material part, as they are so small that their effect upon the operating cycle is negligible.

55 As a result of this invention, it will be noted that by reason of the improved valve mechanism and passage arrangement, a relatively powerful and efficient hammer motor is attained. It will further be evident that by providing cooperating, relatively movable, fluid distributing valve elements respectively controlling the flow of pressure fluid to the opposite ends of the cylinder bore and both capable of being closed at the same time for a substantial portion of the working piston stroke, it is possible greatly to increase the efficiency of the motor, while at the same time a more powerful blow is imparted to the drill steel shank, this, in part, being made possible by effecting simultaneous momentary closure of the supply passages to the opposite ends of the cylinder bore, thereby permitting the hammer piston to strike a largely unimpeded or uncushioned blow to the drill steel shank. It will still further

be evident that by the particular hammer motor structure and the improved arrangement of the parts, a rock drill is provided which is not only extremely efficient in operation but which is also relatively rugged and durable in construction, 5 well adapted to meet the severe demands of service in the drilling of rock. Other uses and advantages of the improved rock drill will be clearly apparent to those skilled in the art.

While there is in this application specifically 10 described one form which the invention may assume in practice, it will be understood that this form of the same is shown for purposes of illustration and that the invention may be modified and embodied in various other forms without de- 15 parting from its spirit or the scope of the appended claims.

What I claim as new and desire to secure by Letters Patent is:

1. In a pressure fluid motor, in combination, 20 a cylinder having a bore, a piston reciprocable in said cylinder bore, and fluid distribution means for supplying pressure fluid to and exhausting fluid from said cylinder bore for effecting reciprocation of said piston comprising means providing 25 a valve chamber, passage means providing fluid supply passages for connecting the opposite ends of said valve chamber with the opposite ends of said cylinder bore, and a pair of cooperating, relatively movable, fluid distributing valves ar- 30 ranged in sliding telescopic relation and movably mounted in said valve chamber for respectively controlling said supply passages.

2. In a pressure fluid motor, in combination, 35 a cylinder having a bore, a piston reciprocable in said cylinder bore, and fluid distribution means for supplying pressure fluid to and exhausting fluid from said cylinder bore for effecting reciprocation of said piston comprising means providing a valve chamber, cooperating, relatively 40 movable, fluid distributing valves reciprocably mounted in said valve chamber, said valves always engaging one another and cooperating to provide a space therebetween, means forming passages leading from said valve chamber to the 45 opposite ends of said cylinder bore at the opposite sides of said piston, said passages controlled by said valves respectively for conducting pressure fluid from said valve chamber to the cylinder bore, and throwing passage means commun- 50 icating with the cylinder bore and controlled by said piston for conducting throwing pressure to said space between said valves.

3. In a pressure fluid motor, in combination, a cylinder having a bore, a piston reciprocable in 55 said cylinder bore, and fluid distribution means for supplying pressure fluid to and exhausting fluid from said cylinder bore for effecting reciprocation of said piston comprising means providing a valve chamber, cooperating, relatively movable, 60 fluid distributing valves movably mounted in said valve chamber and having pressure areas adapted to be subjected to valve throwing pressure, said valves cooperating to provide an internal pressure chamber therein, means for constantly supplying pressure fluid to said internal pressure chamber, means forming passages leading from the opposite ends of said valve chamber to the opposite ends of said cylinder bore for conducting pressure fluid from said valve chamber 65 to said cylinder bore, said passages controlled by said valves respectively, the pressure fluid flowing from said internal pressure chamber past the opposite ends of said valves to said supply passages, and valve throwing means controlled by said pis- 70

ton for conducting pressure fluid from said cylinder bore to pressure areas on said valves for throwing the latter into their different operating positions.

5. In combination, in a motor, a cylinder, a piston reciprocable in said cylinder, and fluid distribution means for said motor including a valve chest, passages leading from said valve chest to the opposite ends of said cylinder, a pair of valve elements arranged within said valve chest and movable relative to each other and to said valve chest and having means cooperating with said valve chest in one position of said valve elements to provide internally of the valve elements a chamber sealed from communication with said cylinder through said passages, and means for delivering motive fluid to said chamber for distribution therefrom under the control of said valve elements through said passages to the opposite ends of said motor cylinder.

5. In combination, in a motor, a cylinder, a piston reciprocable in said cylinder, and fluid distribution means for said motor including a valve chest, passages leading from said valve chest to the opposite ends of said cylinder, a pair of valve elements arranged in said valve chest and movable relative to each other and to said valve chest, an internal fluid supply chamber arranged within said valve elements, said valve elements controlling the flow of pressure fluid from said internal fluid supply chamber to said passages, and means for effecting throwing of said valve elements including surfaces on each of said elements cooperating in the formation of a chamber to which fluid is delivered to effect valve closure and means under the control of said piston for delivering fluid to and venting fluid from said last mentioned chamber.

6. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, a pair of cooperating, relatively movable, fluid distributing valves arranged in said valve chamber, said valves each having an external flange slidably fitting a portion of the valve chamber, means for effecting movement of said valves relative to one another into their different normal operating positions in said valve chamber including means for subjecting the inner adjacent sides of said valve flanges directly to a valve throwing pressure, and means providing fluid supply passages communicating with the ends of said valve chamber directly at the remote sides of said valve flanges respectively for conducting pressure fluid to the opposite ends of said cylinder bore, said valves respectively controlling the flow of pressure fluid through the opposite ends of said valve chamber past the remote sides of said valve flanges to said supply passages.

7. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, cooperating, relatively movable, fluid distributing valves arranged in said valve chamber, said valves each having a sleeve-like body portion, said body portions arranged in telescopic sliding relation and each valve having an annular flange formed externally on the sleeve-like body portion thereof, said

valve flanges slidably fitting portions of the valve chamber, means for effecting movement of said valves relative to one another into their different normal operating positions in said valve chamber including means for subjecting the inner adjacent sides of said valve flanges directly to a valve throwing pressure, and means providing fluid supply passages communicating with the ends of said valve chamber directly at the remote sides of said valve flanges respectively for conducting pressure fluid to the opposite ends of said cylinder bore, said valves respectively controlling the flow of pressure fluid through the opposite ends of said valve chamber past the remote sides of said valve flanges to said supply passages.

8. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, a pair of cooperating, relatively movable, fluid distributing valves reciprocably mounted in said valve chamber, said valves movable into and out of abutting relation, one valve controlling the flow of pressure fluid to one end of said cylinder bore and the other valve controlling the flow of pressure fluid to the other end of the cylinder bore, means for effecting movement of said valves relative to one another into their different normal operating positions in said valve chamber, a pressure fluid supply, means cooperating with said valves respectively for providing a metered flow of pressure fluid from said fluid supply to the opposite ends of said valve chamber and means providing fluid supply passages for conducting pressure fluid from the ends of said valve chamber respectively to the opposite ends of said cylinder bore, said valves respectively controlling the flow of pressure fluid from said fluid supply through the opposite ends of said valve chamber to said supply passages.

9. A pressure fluid motor comprising, in combination, a cylinder, a piston therein, and fluid distribution means for the motor including passage means for supplying operating fluid to the opposite ends of the cylinder at the opposite ends of said piston respectively, an operating fluid supply, valve means including a pair of cooperating, relatively movable, valve elements movable into abutting relation and respectively controlling the flow of operating fluid to the opposite ends of said cylinder, for controlling the communication of said passage means with the fluid supply, and means cooperating with said valve elements for providing metered flow of operating fluid to the opposite ends of the cylinder, said valve elements of said valve means in certain positions thereof momentarily concurrently completely cutting off communication of both of said passage means with said fluid supply.

10. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, a pair of cooperating, relatively movable, fluid distributing valves movably mounted in said valve chamber, means for effecting movement of said valves relative to one another into their different normal operating positions in said valve chamber, means cooperating with said valves providing an in-

- ternal fluid supply chamber within the valves, and means providing fluid supply passages connecting the opposite ends of said valve chamber at the remote sides of said valves respectively to the opposite ends of said cylinder bore, said valves respectively controlling the flow of pressure fluid from said internal fluid supply chamber through the opposite ends of said valve chamber to said supply passages.
- 5 11. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, cooperating, relatively movable, fluid distributing valves movably mounted in said valve chamber, said valves being guided solely at their exterior peripheries and having inwardly directed flanges, means for effecting movement of said valves relative to one another into their different normal operating positions in said valve chamber, means cooperating with said valves providing an internal fluid 10 supply chamber within the valves, means cooperating with said inwardly directed valve flanges for providing a metered flow of pressure fluid from said fluid supply chamber to the opposite ends of said valve chamber, and means providing fluid supply passages connecting the opposite ends of said valve chamber at the remote sides of said valves respectively to the opposite ends of said cylinder bore, said valves respectively controlling the flow of pressure fluid from said fluid supply chamber past said metering-providing means and through the opposite ends of said valve chamber to said supply passages.
- 15 12. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber having a uniform bore and valve seat surfaces at its opposite ends, a pair of coaxial, relatively movable, fluid distributing valves reciprocably mounted in said valve chamber, said valves having sleeve-like body portions and external flanges surrounding said body portions and slidably fitting said valve chamber bore, said sleeve-like body portions of said valves at their remote ends having valve seating surfaces respectively adapted to seat against said valve seat surfaces, means for effecting movement of said valves relative to one another into their different normal operating positions in said valve chamber, and means providing fluid supply passages leading from the opposite ends of said valve chamber respectively to the opposite ends of said cylinder bore, said valves respectively controlling the flow of pressure fluid through the opposite ends of said valve chamber to said supply passages.
- 20 13. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber having a uniform bore and valve seat surfaces at its opposite ends, a pair of coaxial, relatively movable, fluid distributing valves movable into and out of abutting engagement and reciprocably mounted in said valve chamber, said valves having sleeve-like
- body portions and external flanges surrounding said body portions and slidably fitting said valve chamber bore, said sleeve-like body portions of said valves at their remote ends having valve seating surfaces respectively adapted to seat against said valve seat surfaces, means for effecting movement of said valves relative to one another into their different normal operating positions in said valve chamber, and means providing fluid supply passages leading from the opposite ends of said valve chamber respectively to the opposite ends of said cylinder bore, said valves respectively controlling the flow of pressure fluid through the opposite ends of said valve chamber to said supply passages.
- 25 14. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, cooperating, relatively movable, fluid distributing valves reciprocably mounted in said valve chamber, means for effecting movement of said valves relative to one another into their different normal operating positions in said valve chamber, means cooperating with said valves respectively providing metering spaces through which fluid must flow to the opposite ends of said valve chamber, and means providing fluid supply passages for connecting the opposite ends of said valve chamber respectively with the opposite ends of said cylinder bore, said valves respectively controlling the flow of fluid past said metering spaces and through the opposite ends of said valve chamber to said supply passages.
- 30 15. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, cooperating, relatively movable, fluid distributing valves mounted in said valve chamber and reciprocably guided in said valve chamber solely at their exterior peripheries, said valves having internal bores, means for effecting movement of said valves relative to one another into their different normal operating positions in said valve chamber, means including portions projecting within said valve bores respectively for metering the flow of fluid past said valves to the opposite ends of said valve chamber, and means providing fluid supply passages for connecting the opposite ends of said valve chamber respectively to the opposite ends of said cylinder bore, said valves respectively controlling the flow of pressure fluid past said flow-metering means and through the opposite ends of said valve chamber to said supply passages.
- 35 16. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, cooperating, relatively movable, fluid distributing valves reciprocably mounted in said valve chamber, means for effecting movement of said valves relative to one another into their different normal operating positions in said valve chamber, means cooperating with said valves respectively providing metering spaces through which fluid must flow to the op-

posite ends of said valve chamber, and means providing fluid supply passages for conducting pressure fluid from the opposite ends of said valve chamber respectively to the opposite ends of said cylinder bore, said valves respectively controlling the flow of pressure fluid through said metering spaces and through the opposite ends of said valve chamber to said supply passages, and said valves when in certain positions in said valve chamber momentarily completely cutting off the flow of pressure fluid through both metering spaces to said valve chamber ends.

17. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, cooperating, 20 relatively movable, fluid distributing valves reciprocably mounted in said valve chamber, said valves arranged in coaxial relation and movable into and out of abutting relation, means for effecting movement of said valves relative to one another into their different normal operating positions in said valve chamber, means cooperating with said valves respectively providing metering spaces through which fluid must flow to the opposite ends of said valve chamber, and means 30 providing fluid supply passages for conducting pressure fluid from the opposite ends of said valve chamber respectively to the opposite ends of said cylinder bore, said valves respectively controlling the flow of pressure fluid through 35 said metering spaces and through the opposite ends of said valve chamber to said supply passages, and said valves in certain positions thereof in said valve chamber momentarily completely cutting off the flow of pressure fluid through both metering spaces to said valve chamber ends.

40 18. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, a pair of cooperating, relatively movable, annular fluid distributing valves, said valves arranged in coaxial 45 relation and reciprocably mounted in said valve chamber, said valves dividing said valve chamber into inner and outer pressure spaces and end pressure spaces at the remote ends of said valves, means for effecting movement of said valves relative to one another into their different normal operating positions in said valve chamber, means for supplying motive pressure fluid to one of said inner and outer pressure spaces, said valve-movement-effecting means including means for supplying pressure fluid to and exhausting fluid from said other of said inner and outer pressure spaces for effecting movement of said valves into certain of their operating positions, means providing fluid supply passages for connecting said 50 end pressure spaces respectively with the opposite ends of said cylinder bore, said valves respectively controlling the flow of pressure fluid from the motive pressure fluid supply space through said end pressure spaces to said supply passages.

60 19. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, a pair of co-

operating, relatively movable, annular fluid distributing valves, said valves arranged in coaxial relation and reciprocably mounted in said valve chamber, said valves movable into and out of abutting relation, said valves dividing said valve chamber into inner and outer pressure spaces and end pressure spaces at the remote ends of said valves, means for effecting movement of said valves relative to one another into their different normal operating positions in said valve chamber, means for supplying motive pressure fluid to one of said inner and outer pressure spaces, said valve-movement-effecting means including means for supplying pressure fluid to and exhausting fluid from said other of said inner and outer pressure spaces for effecting movement of said valves into certain of their operating positions, and means providing fluid supply passages for connecting said end pressure spaces respectively with the opposite ends of said cylinder bore, said valves respectively controlling the flow of pressure fluid from the motive pressure fluid supply space through said end pressure spaces to said supply passages.

20. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, a pair of cooperating relatively movable, annular, fluid distributing valves, said valves having telescopic sliding engagement and movable into and out of abutting relation, said valves arranged in coaxial relation and reciprocably mounted in said valve chamber, said valves dividing said valve chamber into inner and outer pressure spaces and end pressure spaces at the remote ends of said valves, means for effecting movement of said valves relative to one another into their different normal operating positions in said valve chamber, means for supplying motive pressure fluid to one of said inner and outer pressure spaces, said valve-movement-effecting means including means for supplying pressure fluid to and exhausting fluid from said other of said inner and outer pressure spaces for effecting movement of said valves into certain of their operating positions, and means providing fluid supply passages for connecting said end pressure spaces respectively with the opposite ends of said cylinder bore, said valves respectively controlling the flow of pressure fluid from the motive pressure fluid supply space through said end pressure spaces to said supply passages.

25 21. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chamber, a pair of cooperating, relatively movable, fluid distributing valves reciprocably mounted in said valve chamber, said valves being hollow, means for effecting movement of said valves relative to one another into their different normal operating positions in said valve chamber, means including portions projecting in opposite directions from the opposite ends of said valve chamber within said hollow valves respectively, for providing metered flow of fluid past said valves to the opposite ends of said valve chamber, and means providing fluid supply passages for connecting the opposite ends of said valve chamber respectively to the op-

posite ends of said cylinder bore, said valves respectively controlling the flow of pressure fluid past said metering-providing means and through the opposite ends of said valve chamber to said 5 supply passages.

22. In a pressure fluid motor, the combination comprising a cylinder having a bore, a piston reciprocable in said cylinder bore, and fluid distribution means for supplying pressure fluid to 10 and exhausting fluid from said cylinder bore to effect reciprocation of said piston comprising means providing a valve chamber, a pair of cooperating, relatively movable, fluid distributing valves reciprocably mounted in said valve chamber, 15 said valves each having a sleeve-like body portion and an annular flange surrounding the body portion, said external annular flanges slidably fitting portions of the valve chamber, means for effecting movement of said valves relative to 20 one another into their different normal operating positions in said valve chamber, means including portions projecting in opposite directions from the opposite ends of said valve chamber within the sleeve-like body portions of said valves respectively, for providing a metered flow of pressure fluid past said valves to the ends of said 25 valve chamber, and means providing fluid supply passages for connecting the opposite ends of said valve chamber respectively to the opposite ends 30 of said cylinder bore, said valves respectively controlling the flow of pressure fluid past said metering-providing means and through the opposite ends of said valve chamber to said supply 35 passages.

23. In a pressure fluid motor, the combination comprising a cylinder having a bore, a piston reciprocable in said cylinder bore, and fluid distribution means for supplying pressure fluid to and exhausting fluid from said cylinder bore to 40 effect reciprocation of said piston comprising means providing a valve chamber having valve seat surfaces at its opposite ends, a pair of cooperating, relatively movable, fluid distributing valves reciprocably mounted in said valve chamber, 45 said valves each having a sleeve-like body portion and an annular flange surrounding the body portion, said external annular flanges slidably fitting portions of said valve chamber, the remote ends of said sleeve-like body portions of 50 said valves having annular valve seating surfaces respectively adapted to seat against said valve seat surfaces at the ends of said valve chamber, means for effecting movement of said valves relative to one another into their different normal 55 operating positions in said valve chamber, means projecting in opposite directions from the opposite ends of said valve chamber within the sleeve-like body portions of said valves respectively and cooperating with said valves for providing a metered flow of pressure fluid past said 60 valves to the ends of said valve chamber, and means providing fluid supply passages for connecting the opposite ends of said valve chamber respectively to the opposite ends of said cylinder 65 bore, said valves respectively controlling the flow of pressure fluid past said metering-providing means and through the opposite ends of said valve chamber to said supply 70 passages.

24. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising 75 means providing a valve chamber, a pair of co-

operating, relatively movable, fluid distributing valves movably mounted in said valve chamber, said valves arranged in coaxial relation and being hollow, one valve controlling the fluid supply solely to one end of said cylinder bore and the other valve controlling the fluid supply solely to the opposite end of said cylinder bore, and the pressure fluid flowing to one end of said cylinder bore through both of said hollow valves, means for effecting movement of said valves, relative to one another into their different normal operating positions in said valve chamber, and means providing fluid supply passages leading from the opposite ends of said valve chamber respectively to the opposite ends of said cylinder bore, said valves respectively controlling the flow of pressure fluid through the ends of said valve chamber to said supply passages.

25. A pressure fluid motor comprising, in combination, a cylinder, a piston therein, and fluid distribution means for the motor including passage means for supplying operating fluid to the opposite ends of the cylinder at the opposite ends of the piston respectively, an operating fluid supply, valve means including a pair of cooperating, 25 relatively movable valve elements each movable into a position in which it exerts a pressure to hold the other stationary and respectively controlling the flow of operating fluid to the opposite ends of said cylinder, for controlling the 30 communication of said passage means with said fluid supply, and valve throwing means for subjecting said valve elements to valve throwing pressures to move said valve elements into their different operating positions, said valve throwing 35 means including surfaces on said valve elements subjected by fluid flowing past said valve elements when the latter are in open position to pressures tending to close said valve elements, one of said valve elements when open exerting 40 a pressure which holds the other in closed position, and said valve elements in certain positions thereof momentarily concurrently completely cutting off communication of both of said passage means with said fluid supply.

26. A pressure fluid motor comprising, in combination, a cylinder, a piston therein, and fluid distribution means for the motor including passage means for supplying operating fluid to the opposite ends of the cylinder at the opposite ends of the piston respectively, an operating fluid supply, valve means including a pair of cooperating, relatively movable valve elements movable into abutting engagement and respectively controlling the flow of operating fluid to the opposite 55 ends of said cylinder, for controlling the communication of said passage means with said fluid supply, and valve throwing means for subjecting said valve elements to valve throwing pressures to move said valve elements into their different operating positions, said valve throwing means including portions on at least one of said valve elements subjected by fluid flowing past said valve element to the cylinder, to a force tending to sweep said valve element to its closed position, one of said valve elements being held in closed position by the other valve element abuttingly acting thereon and said valve elements in certain positions when they are out of abutting engagement momentarily concurrently completely cutting off communication of both of said 60 passage means with said fluid supply.

27. A pressure fluid motor comprising, in combination, a cylinder, a piston therein, and fluid distribution means for the motor including pas-

- sage means for supplying operating fluid to the opposite ends of the cylinder at the opposite ends of the piston respectively, an operating fluid supply, valve means including a pair of cooperating, relatively movable valve elements respectively controlling the flow of operating fluid to the opposite ends of said cylinder, for controlling the communication of said passage means with said fluid supply, and valve throwing means for subjecting said valve elements to valve throwing pressures to move said valve elements into their different operating positions including means for subjecting each valve element to closing forces respectively exerted by motive fluid passing it on the way to the cylinder and by fluid pressure controlled by the motor piston in its movement, said valve elements being movable toward and from one another and when in their remote positions momentarily concurrently completely cutting off communication of both of said passage means with said fluid supply and each exerting in its full open position a force for holding the other closed.
28. A pressure fluid motor comprising, in combination, a cylinder, a piston therein, and fluid distribution means for the motor including passage means for supplying operating fluid to the opposite ends of said cylinder at the opposite ends of said piston respectively, an operating fluid supply, valve means including a pair of cooperating, relatively movable valve elements movable into abutting engagement and respectively controlling the flow of operating fluid to the opposite ends of said cylinder, for controlling the communication of said passage means with said fluid supply, and valve throwing means for subjecting said valve elements to valve throwing pressures to move said valve elements into their different operating positions, said valve elements being movable toward one another into abutting relation and from one another out of abutting relation and when in their positions away from one another out of abutting relation momentarily concurrently completely cutting off communication of both of said passage means with said fluid supply, and said valve elements when so completely cutting off communication cooperating in forming a partition extending in the direction of valve movement and having at one side of said partition said operating fluid supply and at the other side thereof surfaces intermittently subjected to pressures to effect positioning of the valve elements in said non-abutting positions.
29. A pressure fluid motor comprising, in combination, a cylinder, a piston therein, and fluid distribution means for the motor including passage means for supplying operating fluid to the opposite ends of the cylinder at the opposite ends of the piston respectively, an operating fluid supply, valve means including a pair of cooperating, relatively movable valve elements respectively controlling the flow of operating fluid to the opposite ends of said cylinder for controlling the communication of said passage means with said fluid supply, and valve throwing means for subjecting said valve elements to valve throwing pressures to move said valve elements into their different operating positions, said valve throwing means including for each of said valve elements means associated with the latter and subjected to a valve closing pressure by fluid flowing past said valve element to the cylinder and means subjected to a supplemental valve closing pressure controlled by the position of the motor piston, said valve elements being movable

toward and from one another, each of said valves when in its full open position exerting a force for holding the other closed, and said valve elements movable to effect concurrently interruption of communication of each of said passage means with said fluid supply.

30. In a pressure fluid motor, the combination comprising a cylinder having a bore, a piston reciprocable in said cylinder bore, a valve chest providing a chamber, fluid distribution passages leading from said valve chamber to the opposite ends of said cylinder bore, valve means in said chamber for controlling the flow of motive fluid from said chamber to said distribution passages including relatively movable fluid distributing valve elements, said valve elements movable to positions in which they concurrently interrupt communication between said chamber and said fluid distribution passages and simultaneously cooperate in providing a partition which divides said chamber from end to end and at one side of which partition both of said distribution passages open into the chamber, a source of operating fluid communicating with said chamber at a point separated by said partition, when the same is formed, from said fluid distribution passages, and means for moving said valve elements into their different operating positions including passage means for delivering valve throwing fluid to said valve elements to act upon the same at the other side of said partition.

31. A pressure fluid motor comprising, in combination, a cylinder, a piston therein, and fluid distribution means for the motor including passage means for supplying operating fluid to the opposite ends of the cylinder at the opposite ends of the piston respectively, an operating fluid supply, valve means including a pair of cooperating, relatively movable valve elements respectively controlling the flow of operating fluid to the opposite ends of said cylinder for controlling the communication of said passage means with said fluid supply, and valve throwing means for subjecting said valve elements to valve throwing pressures to move said valve elements into their different operating positions including oppositely extending flanges on each of said valve elements respectively continuously and intermittently subjected to valve closing forces when said valve element is in open position, said valve elements being movable toward and from one another, each of said valve elements when in its full open position exerting a force for holding the other closed, and said valve elements movable to effect concurrently interruption of communication of each of said passage means with said fluid supply.

32. A pressure fluid motor comprising, in combination, a cylinder, a piston therein, and fluid distribution means for the motor including passage means for supplying operating fluid to the opposite ends of the cylinder at the opposite ends of the piston respectively, an operating fluid supply, valve means including a pair of cooperating, relatively movable valve elements respectively controlling the flow of operating fluid to the opposite ends of said cylinder for controlling the communication of said passage means with said fluid supply, and valve throwing means for subjecting said valve elements to valve throwing pressures to move said valve elements into their different operating positions including portions on each of said valve elements continuously subjected by fluid flowing past said valve elements to the cylinder to valve closing forces when said valve elements are in open position, and means

providing oppositely facing pressure areas intermittently subjected to valve closing forces to supplement said first mentioned forces and close said valve elements in alternation, said valve elements being movable toward and from one another, each of said valve elements when in its full open position exerting a force for holding the other closed, and said valve elements movable to effect concurrently interruption of communication of each of said passage means with said fluid supply.

33. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chest, a pair of cooperat-

ing, relatively movable, fluid distributing valves movably mounted in said valve chest for controlling the supply of pressure fluid to the opposite ends of said cylinder bore, said valves arranged in coaxial relation and being hollow, and the pressure fluid flowing to the rear end of said cylinder bore through both of said hollow valves, means for effecting movement of said valves relative to one another into their different normal operating positions in said valve chest, and means providing fluid supply passages leading from the opposite ends of said valve chest respectively to the opposite ends of said cylinder bore, said valves respectively controlling the flow of pressure fluid through the ends of said valve chest to said supply passages.

JOHN CLARK CURTIS.

CERTIFICATE OF CORRECTION.

Patent No. 2,224,859.

December 17, 1940.

JOHN CLARK CURTIS.

It is hereby certified that error appears in the printed specification of the above numbered patent requiring correction as follows: Page 3, second column, line 47, for "ls" read --is--; page 5, second column, line 63-64, for "pressure" read --pressures--; page 8, second column, line 74, claim 21, for "en" read --ends--; page 9, second column, line 10, claim 24, after the word "valves" strike out the comma; and that the said Letters Patent should be read with this correction therein that the same may conform to the record of the case in the Patent Office.

Signed and sealed this 4th day of February, A. D. 1941.

(Seal)

Henry Van Arsdale,
Acting Commissioner of Patents.
